LEAD PENCIL

Original Filed Dec. 13, 1922

UNITED STATES PATENT OFFICE

EARL F. PIERCE AND JOHN DAVID DICKINSON, OF CHICAGO, ILLINOIS; CENTRAL TRUST COMPANY OF ILLINOIS, ADMINISTRATOR OF SAID EARL F. PIERCE, DECEASED, ASSIGNOR TO FLORENCE E. PIERCE

LEAD PENCIL

Application filed December 13, 1922, Serial No. 606,581. Renewed March 9, 1929.

Our invention relates to improvements in lead pencils and is particularly concerned with improvements in lead pencils of the refillable type.

5 The objects of our invention are:

First: To provide a lead pencil of the refillable type comprising means for holding a plurality of leads, means for expelling a lead from one end of said pencil, and means 10 for conveniently supplying a new lead to said lead expelling means when the preceding lead has been substantially used up;

Second: To provide a pencil of the character described, comprising a magazine which 15 will hold a plurality of pencil leads, and means for easily and quickly transferring the leads, one at a time, from said magazine to said lead expelling means;

Third: To provide a pencil such as described, in which the magazine is in the form 20 of a cartridge which can be easily and quickly inserted in and removed from the pencil barrel;

Fourth: To provide a new article of manufacture comprising a cartridge containing a 25 plurality of pencil leads;

Fifth: To provide a cartridge of the character described, comprising means for holding the leads in proper position to expedite 30 the insertion of the cartridge in the pencil;

Sixth: To provide a lead pencil such as described above, comprising means for automatically displacing the lead retaining means from the cartridge as the latter is inserted in 35 the pencil;

Seventh: To provide a lead pencil comprising a lead guiding tube, a lead expelling rod mounted to slide in said lead guiding tube for the purpose of expelling the lead 40

therefrom, the said lead expelling rod being provided with a nut for co-acting with internal threads in the barrel of the pencil whereby the lead can be gradually expelled therefrom, and means for easily and quickly retracting said lead expelling tube to its initial position; and

Eighth: To provide a lead pencil comprising a lead guiding tube having a lateral entrance, a gate for closing said entrance, a rod 45 for expelling the lead from said lead guid-

ing tube, and means for simultaneously opening said closure to permit the entrance of the lead into said guiding tube and retracting said lead expelling rod to its initial position.

The above and other objects of our invention will appear as this description progresses, reference being had to the accompanying drawings, in which

Figure 1 is a side elevation of our improved lead pencil;

Figure 2 is a central longitudinal section therethrough;

Figure 3 is a longitudinal section through one of the elements of our improved pencil;

Figure 4 is a similar view through the lead 65 guiding tube;

Figures 5 and 6 are transverse sections taken on lines 5—5, and 6—6 of Figure 4;

Figures 7, 8 and 9 are transverse sections taken on lines 7—7, 8—8 and 9—9 respectively of Figure 2;

Figure 10 is a longitudinal section through the cartridge forming a part of our invention; and

Figure 11 is an end view of the cartridge.

Throughout the several views, similar reference characters will be used for referring to similar parts.

Referring to the drawings, our improved pencil comprises the usual barrel 10, the upper end of which is internally threaded as shown at 11, and the lower end of which is provided with the usual guiding point 12, which is connected with the lower end of the barrel by means of the screw threaded connection 13. The lower end of the barrel is counterbored slightly to provide a shoulder 14 against which the disk 15 rests.

Projecting downwardly from the disk 15 and rigidly secured thereto is the lead guiding tube 16 which is preferably located centrally of the barrel and has a longitudinally extending slot 17, formed in one side thereof, this slot being slightly longer than the lead which is to be received by the lead guiding tube. The lower end of the lead guiding tube projects into a counterbore 18, formed in the upper end of the lead guiding point 12.

For expelling the leads from the lead guiding tube 16 we provide the lead expelling rod

19 which is slidably mounted in the barrel and the lower end of which extends into the upper end of the lead guiding tube 16. Extending from opposite sides of the upper end of the lead expelling rod 19 is a leaf spring 20, which first extends outwardly and then substantially parallel with the adjacent wall of the barrel. A nut segment 21 is secured to the free ends of each of the spring leaves or extensions 20 and is adapted to engage 10 the internal threads of the barrel.

A bifurcated rod comprising the two bifurcations 22, which are connected at their top and bottom ends by the cylindrical sections 23 and 24 respectively, is slidably mounted in the barrel and in a collar 25 secured in the upper end of the barrel 10. The bifurcations of this rod pass between the two nut segments 21 and on opposite sides of the lead expelling rod 19.

20. A cup-shaped member 26 is secured to the upper or outer end of the bifurcated rod which serves the double purpose of holding an eraser 27 and forming a handle whereby the bifurcated rod can be rotated. This cup is secured to the adjacent end of the bifurcated rod by means of the screw 28. If desired, a suitable cap 29 may be provided for this cup-shaped handle. A clip 30 may be 30 secured to the upper end of the pencil, in the manner shown, if so desired.

From the above description it will be clear that when the bifurcated rod is rotated by means of its operating handle, the sides of 35 its bifurcations will engage the edges of the leaf springs or extensions 20, and that in this manner the nut segments can be rotated either to advance or retract the lead expelling rod 19 to adjust the lead as may be desired.

40. To provide means for easily and quickly retracting the lead expelling rod 19 when it has been actuated to its lowermost position, we secure a ring 31 to the lower end of the bifurcated rod. The upper end of this ring 45 has a tapered bore 32 formed therein, which provides cam faces for engaging the curved portions of the leaf springs 20 when the bifurcated rod is pulled outwardly and bending them inwardly so as to disengage the nut 50 segments 21 from the threads 11. By this means all that is necessary to retract the lead expelling rod 19 is to grasp the cup shaped handle 26 and pull it outwardly. The movement of the bifurcated rod will cause 55 a disengagement of the nut segments from the threads and then if the movement of the bifurcated rod is continued the lead expelling rod 19 can be withdrawn from the lead expelling tube to the full limit of its movement. Upon pushing inwardly on the bifurcated rod, the cam ring 31 will disengage 60 the leaf springs 20 and permit the nut segments 21 to again engage the threads 11.

In Figures 2, 8, 9 and 10 we have illustrated the construction of a magazine or

cartridge which comprises a tubular member 33, which is split longitudinally and provided with the longitudinally extending in-turned flange 34, the upper end of which projects beyond the inturned flange 35 at this 70 end. Pencil leads 36 can be filled into this magazine and held in their proper position adjacent to the walls of the magazine by means of the plug 37, which is inserted in the lower open end of the magazine and is provided with a longitudinally extending slot for receiving the flange 34. The outer end of this plug is provided with a head 38 which prevents the leads from escaping from the magazine. To insert the cartridge thus formed into the pencil, where it will function as a magazine, the lead guiding point 12 is unscrewed from the barrel of the pencil and the upper end of the cartridge is positioned so that the opening therein will register with the end of the lead guiding tube 16. The tubular member is then pushed inwardly whereupon the end of the lead guiding tube will displace the plug 37 from the cartridge, thus serving to hold the leads in their proper position while the tubular member and its contained leads are being inserted into the pencil barrel. The point 12 can then be replaced. It will be noted that the lower side of the disk 15 is provided with a transversely extending slot 40 for receiving the upper end of the flange 34 so as to hold the magazine in proper relation to the slot 17 in the lead guiding tube.

For the purpose of holding a lead in the lead guiding tube so as to enable it to be properly expelled therefrom by the rod 19, we provide a gate 41 which forms an extension of the bifurcated rod and is slidably mounted in the slot 17 formed in the lead guiding tube. The lower end of this gate is tapered as shown at 42 so as to make it impossible for the lower end of the gate to engage the end of any one of the leads in the magazine and thus prevent the closing of the gate. The disk 15 is suitably slotted as shown at 43 to permit the passage of the gate 41.

From the above description, it will be seen that all that is necessary to do to reload the pencil after a lead has been used to such an extent that the rod 19 can no longer expel it from the point 12 is to hold the pencil in a horizontal position, and pull outwardly upon the handle 26 thereby retracting the lead expelling rod 19 from the tube and removing the gate 41 from the longitudinal slot in the lead receiving tube. The pencil is then rotated clockwise (Fig. 4) a complete revolution which will insure one of the leads dropping through the slot 17 into the lead guiding tube. It will, of course, be understood that when the leads are in a certain position it will not be necessary to rotate the pencil through a complete revolution but this may be done to insure the proper loading of the 130

pencil irrespective of the number of leads contained in the magazine and the position of the lead guiding flange 34. After the pencil has been rotated as explained above, the bifurcated rod is returned to its initial position, thus leaving the lead expelling rod in its initial position and simultaneously closing the slot 17. The handle 26 can then be manipulated to turn the bifurcated rod and the nut segments 21 so as to project the lead 10 the desired distance from the point 12 whereupon the pencil is ready for use.

While we have described the details of construction of the preferred embodiment of our invention, it is to be clearly understood that 15 our invention is not limited to these details of construction but is capable of other adaptations and modifications within the scope of the appended claims.

Having thus described our invention, what 20 we claim is:

1. A lead pencil comprising a barrel having a lead guiding tube centrally mounted in one end thereof, the opposite end of said barrel being internally threaded, said tube 25 having a lead receiving slot extending longitudinally thereof, a lead expelling rod slidably mounted in said barrel and having its lower end extending into said tube, a pair of spring projections extending outwardly 30 from the opposite end of said rod, a nut segment secured to the outer ends of each of said spring extensions for engaging the threads in said barrel, a bifurcated rod slidably mounted in the upper end of said barrel, the 35 bifurcations of said rod passing between said nut segments and on opposite sides of said lead expelling rod, an operating handle secured to the upper end of said bifurcated rod, a cam ring secured to the opposite end of 40 said bifurcated rod for engaging said spring extensions to disengage said nut segments from said threads, a gate extending from said bifurcated rod for closing said lead receiving slot, and a magazine surrounding said 45 tube for holding a plurality of leads and communicating with the slot in said tube.

2. A lead pencil comprising a barrel having a lead guiding tube mounted in one end thereof, the opposite end of said barrel being internally threaded, said tube having a lead receiving slot extending longitudinally thereof, a lead expelling rod slidably mounted in said barrel and having its lower end extending into said tube, a spring projection extending outwardly from the opposite end of said rod, a nut segment secured to the outer end of said spring extension for engaging the threads in said barrel, a second rod slidably mounted in the upper end of said barrel eccentrically of said lead expelling rod, an operating handle secured to the upper end of said second rod, a cam secured to the opposite end of said second rod for engaging said 65 spring extension to disengage said nut seg-

ment from said threads, a gate extending from said second rod for closing said lead receiving slot, and a magazine surrounding said tube communicating with the slot in said tube.

3. A lead pencil comprising a barrel, the upper end of which is internally screw threaded, a lead guiding tube mounted in the other end of said barrel and having a longitudinally extending slot formed therein, a lead expelling rod slidably mounted in said barrel and having one end extending into said lead guiding tube, a nut segment secured to the other end of said lead expelling rod, a second rod slidably mounted in the upper end of said pencil, means whereby said second rod can be reciprocated in said barrel, means carried by said rod for disengaging said nut segment from said threads, and a gate carried by the lower end of said rod for closing said slot.

4. A lead pencil comprising a barrel, the upper end of which is internally screw threaded, a lead guiding tube mounted in the other end of said barrel and having a longitudinally extending slot formed in one side thereof, a lead expelling rod having one end extending into said lead guiding tube, a nut segment secured to the other end of said lead expelling tube, a gate for closing the slot in said tube, and common means for simultaneously opening said gate and retracting said lead expelling rod from said tube, there being a lost motion connection between said lead expelling rod and said last-named means to permit said last-named means to be returned to its initial position without moving said lead expelling rod.

5. A lead pencil comprising a barrel, the upper end of which is internally screw threaded, a lead guiding tube mounted in the other end of said barrel and having a longitudinally extending slot formed in one side thereof, a lead expelling rod having one end extending into said lead guiding tube, a nut segment secured to the other end of said lead expelling tube, a gate for closing the slot in said tube, and means for simultaneously opening said gate and retracting said lead expelling rod from said tube.

6. In a lead pencil a lead guiding tube, having a longitudinally extending slot formed therein, a magazine surrounding said lead guiding tube and communicating therewith, a gate for closing said slot, and means whereby said gate can be opened and closed.

7. In a lead pencil a lead guiding tube having a longitudinally extending slot formed therein, a magazine surrounding said lead guiding tube and communicating therewith, a gate for closing said slot, and means for moving said gate longitudinally to either open or close said slot.

8. A pencil comprising a barrel, a lead guiding tube positioned therein, a lead carry-

- ing cartridge surrounding the guide tube but detachable therefrom as a unit, a guide flange formed in the cartridge, and a side opening in the guiding tube alined with the guide flange, interlocking means on the cartridge and on the guide tube for holding the guide flange and said side opening in alinement and a plunger for adjustably advancing the lead in the guide tube.
9. In a lead pencil a lead guiding tube having a longitudinally extending slot therein, lead containing means around said tube communicating therewith, closing means for said slot and means for actuating said closing means.
10. In a lead pencil a lead guiding tube having a longitudinally extending slot therein, lead containing means around said tube communicating therewith, a flange on said tube containing means extending along said slot for directing supply leads into said tube through said slot, closing means for said slot and means for actuating said closing means.
11. In a lead pencil a lead guiding tube having a longitudinally extending slot therein, lead containing means around said tube communicating therewith, guiding means cooperatively associated with said slot for directing supply leads into said tube and closing means for said slot.
12. In a lead pencil a lead guiding tube having a longitudinally extending slot therein, a lead supply compartment about said tube communicating therewith, lead guiding means extending across said compartment in a fixed position relative to said slot for directing leads thereinto and closing means for said slot.
13. In a lead pencil a lead guiding tube having a longitudinally extending slot therein, a lead supply compartment about said tube communicating therewith, lead guiding means extending across said compartment in a fixed position relative to said slot for directing leads thereinto, closing means for said slot and means for reciprocating said closing means into and out of operative position.
14. In a lead pencil a lead guiding tube having a slot extending longitudinally thereof for the reception of supply leads, removable lead supply magazine surrounding said lead guiding tube and communicating therewith, closing means for said slot and a flange on said magazine cooperatively associated with said slot arranged to obstruct a portion of said magazine and direct leads into said slot.
15. In a lead pencil a lead guiding tube having a slot extending longitudinally thereof for the reception of supply leads, removable lead supply magazine surrounding said lead guiding tube and communicating therewith, a flange on said magazine cooperatively associated with said slot arranged to obstruct a portion of said magazine and direct leads into said slot and a gate adapted to fit within said slot for closing the same.
16. In a lead pencil a lead guiding tube having a slot extending longitudinally thereof for the reception of supply leads, removable lead supply magazine surrounding said lead guiding tube and communicating therewith, a flange on said magazine cooperatively associated with said slot arranged to obstruct a portion of said magazine and direct leads into said slot, closing means for said slot and means for reciprocating said closing means into and out of operative position.
- In witness whereof, we hereunto subscribe our names this 7th day of December, 1922.
- EARL F. PIERCE.
JOHN DAVID DICKINSON.
